Primary Examiner — Marcus Jackson(74) *Attorney, Agent, or Firm* — Schwabe Williamson & Wyatt(57) **CLAIM**

We claim the ornamental design for the lighting for a pallet truck, as shown and described.

DESCRIPTION

FIG. 1 is a left, front isometric view of a lighting configuration for a lighting for a pallet truck;

FIG. 2 is a front view of the lighting for a pallet truck of FIG. 1;

FIG. 3 is a top view of the lighting for a pallet truck of FIG. 1; and,

FIG. 4 is a right side view of the lighting for a pallet truck of FIG. 1, the left side view being a mirror image of the right side view.

In FIGS. 1-4, the broken lines indicate environmental features and form no part of the claimed design.
